UNITED STATES PATENT OFFICE.

ARTHUR FEINBERG, OF NEW YORK, N. Y.

STRESS-BREAKING DENTAL ATTACHMENT.

Application filed May 18, 1923. Serial No. 639,938.

To all whom it may concern:

Be it known that I, ARTHUR FEINBERG, a citizen of the United States, residing in the county and State of New York, have invented a certain new and useful Stress-Breaking Dental Attachment, of which the following is a specification.

This invention is an attachment for artificial dentures and provides means whereby such dentures may be attached to the natural teeth in such a manner as to preclude the transmission to the natural teeth, stresses and strains which would be apt to in time effect and cause loosening of the natural teeth.

It is known in the practice of dentistry that when bridgework or plate-work is anchored to natural teeth or roots in a firm or rigid manner, stresses and strains are communicated to the natural teeth from the artificial denture in such a manner, as to cause irritation, and loosening of the natural teeth.

The attachment of my invention is so arranged and constructed as to obviate or remove all the strains from the natural teeth, and transmit them directly to the ridge or gums of the mouth, that is, the forces of mastication which are brought to bear upon the artificial denture are transmitted to the gums or ridges, and the natural teeth are available merely for the purpose of maintaining the denture at all times, in proper and normal relation and position to the natural teeth, and also engages with the gums and ridges, so that it does not permit the denture to draw away or to become dislodged.

A further object of my invention is to overcome the difficulties encountered in converging, diverging and tilting angles of the natural teeth, when such teeth are utilized as abutments for artificial dentures.

A further and particular object of my invention is to provide means whereby repairs and adjustments can easily be made without detriment to the artificial denture.

The attachment of my invention, consisting of two members, is so designed, that one member can easily be released or disconnected from the other member, for the purpose of making such repairs and adjustments.

Adjustments are made for the purpose of allowing more play or working space between the two members, when such play or working space is lost through resorption or absorption of the alveolar process.

Various methods and appliances have been

made to overcome the difficulties mentioned, and the present invention relates to improvements on these devices and obviates the difficulties and objections mentioned, and more so to furnish a more simple compact and efficient means for connecting a denture to natural teeth.

It will be apparent from the hereinafter detailed description and claims, when read in conjunction with the accompanying drawings:

Figure 1, is perspective view of a metallic plate to be secured to a clasp or crown, and is termed the clasp part.

Figure 2, is perspective view of a metallic plate to be secured to a denture or bridge and is termed the denture part.

Figure 3, is a perspective view of the attachment assembled.

Figure 4, is a longitudinal sectional view of the attachment when in normal position.

Figure 5, is a longitudinal sectional view of the attachment when one member is raised and the other member lowered.

Figure 6, shows its application to the natural teeth and denture.

In the drawings, 10 designates the clasp part, consisting of a metallic plate to be firmly secured to a crown or clasp as at 25, by soldering or otherwise, and is bent at its lower end to form a leg 11, which is slotted as at 12, Figure 1. The denture part 13, as in Figure 2, consisting of a metallic plate, preferably of gold, embodies a loop 14 which has its free ends bent and turned upwardly and in the same line, forming two integral vertical tongues, 15 and 16 as in Figure 2. The free end of tongue 16 resting against and abutting with the base of the upper tongue 15, and both tongues being parallel to the clasp part as in Figure 3. The lower tongue 16, engages with the slot 12 of the clasp part 10 for sliding movements, whereas the upper tongue 15 serving as a protection, or safeguard between the plate 26 and clasp part 10, as in Figure 6, thereby permitting free and unobstructed movements of the parts mentioned. Tongue 15, not only being parallel to, but corresponding in size as to the width and height of the clasp part 10 as in Figure 3. The loop 14 which is formed between the bases of the tongues 15 and 16 is provided for the reception of and engagement with the leg 11.

To assemble the clasp part 10 with the denture part 13, the free end of the tongue 16 is slightly opened, and passed through

the aperture 12 of the clasp part 10 as in Figures 3 and 4. This will bring the parts 10 and 13 in normal position and relation to each other, and allowing free movements between them. The free end of tongue 16 is then brought back to its original position, thereby preventing their separation.

The clasp part 10 with its leg extending outwardly is soldered or otherwise connected 10 to the side of the crown or clasp as at Figure 6. In securing the denture part 13 to the denture 26, the denture is brought to bear upon the loop 14 and against the side of the tongue 15, as in Figure 6, it is then 15 soldered or vulcanized as the case may be.

A salient feature resides in the fact that whereas the artificial denture is resting against the side of the tongue 15, tongue 16 is entirely free and unobstructed by the 20 denture, thus permitting adjustments and repairs to be made by opening laterally the free end of the tongue 16, making the necessary adjustments, and then closing it again, when such repairs and adjustments are completed. As the denture part cannot break, 25 the only member being susceptible to fracture is the clasp part, and that has been provided for by my invention, and as explained above.

30 Having fully described my invention, what I desire to claim is:

1. A dental attachment embodying a slotted clasp part, a denture part comprising a loop, the free ends of which are bent into alinement and form two vertical tongues, 35 one of which is adapted to pass through the slot of the clasp part and the other of which is adapted to rest against an artificial denture, whereby slight movement between said 40 artificial denture and clasp part is permitted without binding.

2. A dental attachment embodying a denture part comprising two alined tongues, a 45 loop uniting the bases of the tongues and normally maintaining said tongues in alined relation, and a clasp part extending into the loop and provided with an opening through which one of the tongues extend.

3. A dental attachment embodying a slotted clasp part, a denture part comprising a 50 loop, the free ends of which are bent upwardly into substantial alinement to form two vertical tongues, the free end of one tongue passing through the slot of the clasp

part and abutting with and resting against 55 the base of the other tongue whereby inadvertent separation of the denture part from the clasp part is precluded.

4. A dental attachment embodying a clasp part comprising a plate having a slotted projection, in combination with a denture part 60 provided with two vertical tongues, one face of one tongue being adapted for engagement with the side of a dental plate and being substantially equal in width and height to the width and height of the plate of the clasp part and adapted to form a bearing surface for the latter, and the other tongue passing through the slot in the projection of the clasp part and abutting the base of the other 70 tongue.

5. A dental attachment embodying a slotted clasp part, a denture part comprising a loop, the free ends of which are bent into alinement to form two integral vertical tongues, 75 the upper tongue being adapted for engagement with a dental plate and the lower tongue passing through the slot of the clasp part to normally maintain the parts in assembled relation, said lower tongue being 80 adapted to be bent laterally and out of alinement with the upper tongue to permit the release of the clasp part for the purpose of repairs and adjustment and to allow return of said clasp part into cooperative position 85 when such repairs and adjustments are completed, without disturbing the relationship between the denture part and an associated denture.

6. A dental attachment embodying a denture part comprising a substantially C-shaped body, at the upper end of which is formed an upwardly extending tongue, one face of which constitutes a bearing surface for a cooperating clasp part, and the lower 90 end of which body is provided with an upstanding tongue positioned in substantial alinement with the upper tongue and terminating at, and bearing against the base of the upper tongue, in combination with a co-operating clasp part comprising a plate 100 adapted to bear against the contiguous face of the upper tongue and provided with a projecting portion extending into the C-shaped body of the denture part and having 105 an opening through which the lower tongue extends.

ARTHUR FEINBERG.
